UNITED STATES PATENT OFFICE.

HENRY LUBÉ, OF COLLEGE POINT, NEW YORK, ASSIGNOR TO RADIO MOTION PICTURE PHON. CORP., OF LONG ISLAND CITY, NEW YORK, A CORPORATION OF MASSACHUSETTS.

MOTOR.

Application filed October 31, 1922. Serial No. 598,098.

It is an object of the present invention to provide a motor, and more particularly a motor which is adapted for use in connection with the driving of apparatus such as 5 phonographs, motion picture projectors, etc.

It is well appreciated that numerous attempts have been made to operatively connect a motion picture projector and a talking machine, but these attempts for the most 10 part have not met with success, incident to the fact that great care must be utilized in synchronizing the movement of both of the devices, so that a proper ratio of operation will exist between the two, insuring a correct light image projection, and a sound wave production in register with each other.

Thus it is a further object of this invention to provide a device of the character stated which may be utilized in connection 20 with the simultaneous driving of both a talking machine and a motion picture projector in such a manner that these machines will operate in synchronism, the sound waves emanating from the first named machine being in absolute register with the light images 25 projected by the last named device.

Another object of this invention is that of furnishing a motor of any desirable type which will act as a driving element, and 30 serve to operate a driven element, the latter being connected with a projecting machine, as well as the turntable of a talking machine in such a manner that both of these elements will be driven at the proper speed necessary 35 to their correct operation.

Still another object is that of constructing mechanism connecting the driving and driven elements aforementioned, one with the other, so that the speed of the driven 40 member will at all times be constant, thus preventing variations in the speed of the driven element which would be detrimental to the result produced.

I wish it understood, however, that al- 45 though as aforesaid the present invention is particularly intended and conceived with a view of properly synchronizing the movements of a talking machine of any desirable type, with the movements of a motion picture projector, such as has for example 50 been shown in my co-pending application Serial Number 589,520 on a motion picture machine, which application was filed Sep-

tember 21, 1922, that my present invention is applicable to numerous other associations. 55

With these and other objects in mind, the invention includes essentially a driving and a driven member, together with means connecting these elements one with the other in such a manner that the speed of the 60 driven shaft will be constant, so that in the event that both a projecting machine and a talking machine are connected to this latter element, both of these machines will operate synchronously. 65

Reference is had to the attached sheets of drawings as illustrating one practical embodiment of my invention, and it will be seen in these drawings that:

Fig. 1 is a perspective view of a talking machine of conventional construction within which my improved mechanism is disposed, the latter serving to operate this machine, and being coupled with a motion picture projector of the type illustrated in 70 my co-pending application afore-referred to. 75

Fig. 2 is a side view of the mechanism involved in my invention and showing the same as applied to the apparatus for which it is particularly designed. 80

Fig. 3 is a transverse sectional view taken along the line 3—3 and in the direction of the arrows indicated in Fig. 2.

Fig. 4 is a side view of a detail of construction, showing a part of the invention, 85 and

Fig. 5 is a sectional plan view taken along the line 5—5 and in the direction of the arrows indicated in Fig. 4.

Referring primarily to Fig. 1 it will be 90 noted that the reference numeral 10 indicates a projecting machine of the type noted in my previous application, and I wish it understood that any desirable type of projecting machine may be operated by means 95 of the mechanism, hereinafter set forth, and that this driving is effected in any suitable manner such as for example by connecting the driving shaft 11 of the projecting machine with a shaft 12 by means of a universal 13, the shaft 12 being in turn connected by means of a universal 14 with a driving shaft 15 extending beyond the cabinet of the talking machine 16, or other housing utilized for enclosing the mecha- 100 105 nism.

With regard to the mechanism serving to connect the shaft 15 with the turntable of the talking machine, it will be noted, reference being had to Fig. 2 that this shaft 5 preferably mounts a worm 17 which meshes with the teeth of a worm wheel 18 secured to a turntable spindle 19, which latter in the usual manner is mounted in suitable bearings, and extends beyond the deck 10 of the talking machine, and carries the turntable 21. Thus assuming that the shaft 15 is rotated in a manner hereinafter described, by a suitable motor 22 it will be appreciated that incident to the universals 14 and 13, 15 and the shaft 12 that the driving shaft 11 of the projector 10 will be rotated to operate the mechanism of the latter. Also the worm 18 carried by the driving shaft 15 will rotate the spindle 19, and thus the turntable 21 will be properly moved.

Also with a view of insuring a proper driving ratio between the mechanism of the projector 11 and the turntable, it will be noted, assuming for example that the shaft 25 of the projector is to be rotated at a twelve to one ratio with respect to the turntable spindle, and assuming that the worm 17 and gear 18 are of a twelve to one ratio, that for each revolution of the driving shaft 30 15 one twelfth of a revolution of the spindle 19 will result so that the projection of the light images, and the sound waves will be obviously synchronized, it being understood that if a different ratio exists between the 35 revolutions of the turntable and the driving shaft of the projecting machine, that these parts may again be caused to operate in synchronism one with the other by simply altering the ratio of the elements 17 and 18.

Now with a view of properly connecting the motor 22 with the driving shaft 15 in such a manner that the variations in the speed of the former will not be transmitted 45 to the latter, but that this last named element will rotate at a constant R. P. M., it will be noted that I affix to the shaft 15 a belt pulley 23 and a similar pulley 24 of a smaller size is affixed to the driving shaft of 50 the motor, these pulleys being connected together by means of a belt 25. An idler roller 26 normally bears against the belt 25 in such a manner as to tension the same in order to insure a direct and positive 55 drive. This roller is carried by an arm 27 which may form one part of a bell crank, it being noted that its body is supported adjacent its upper end in such a manner that it is capable of being rocked, this support 60 being conveniently effected by means of a pivot pin 28. A spring 29 has one of its ends attached to a fixed portion of the driving mechanism assembly, and its opposite end is connected with the arm 27 so that the 65 roller 26 is normally caused to bear against

the belt 25, and thus to tension the same as has been indicated in full lines in Fig. 3. The inner face of the arm 27 may be grooved as has been indicated at 30, and bearing against this groove is the outer face of a 70 conical collar 31, the latter being mounted for sliding movement upon the shaft 15, and being attached to the movable end of a centrifugal governor 32, the opposite end of which is fixedly attached to the shaft 15. 75 Thus during normal operation of the mechanism the shaft 15 will rotate in direct proportion to the rotation of the motor shaft. However, assuming that this latter shaft exceeds a predetermined speed the governor 80 32 will act to draw the collar 31 towards the arm 27, which will result, incident to the engagement of the collar with the groove 30, in the arm being moved outwardly to a greater or less extent in proportion to the 85 speed of the motor shaft. This will cause the roller 26 to move outwardly to slacken the tension upon the belt 25, and if the speed of the motor 22 is greatly in excess of its required speed the arm 27 will finally swing 90 to the position shown in dotted lines in Fig. 3 at which point the slackness of the belt 25 will be such as to permit a material amount of slippage between the driving and driven elements, so that by this expedient a substantially constant speed of the driving shaft 95 15 is assured, irrespective of the revolutions on the part of the motor 22.

Finally to provide means serving to disengage the driving and driven elements, and 100 to cause the latter to be brought to a stop, it will be seen that the bell crank of which the arm 27 forms one part, is provided with another arm 32, which extends beyond the pin 28, this arm being formed with an inclined lower surface 33 against which a pin 34 may bear, the latter being in turn secured to a shaft 35 to which there is connected a handle 36. Thus upon this handle 105 being operated, the pin 34 will bear against the underside of the arm 32 and move the same to rock the arm 27 to the position shown in dotted lines in Fig. 3 and the driving elements are brought to an immediate stop upon this occurring by means of a brake 110 shoe or strip 37 which may be attached to the bell crank and bear against the upper face of the pulley 23 to bring the same to a stop.

Thus it will be appreciated that the objects 115 of this invention have been accomplished in that assuming that the motor 22 is making 400 R. P. M. the ratio of the pulleys 24 and 23 is such with respect to each other that the shaft 15 will be driven at approximately 700 120 R. P. M. which speed is a proper one for correct operation of the driving shaft 11 of the projecting machine. Also due to the reduction mechanism afforded by the worm 125 and worm wheel the spindle will be turned 130

at a speed consistent with the production of proper results on the part of the talking machine, and thus the movement of both mechanisms will be synchronized and co-ordinated one with the other.

Further, in the event that the speed of the motor should fluctuate, it will be seen primarily that the reduction offered by the mechanism afore-described will operate to diminish undesirable results due to the fact that these fluctuations will hardly be perceptible, but in the event that the speed of the motor becomes excessive it will be understood that the governor will immediately act to permit a slippage in the connection existing between the motor shaft and the shaft 15 so as to maintain the proper ratio.

It will be understood that numerous modifications of structure and different associations of parts might readily be resorted to without in the least departing from the spirit of my invention as defined by my claims; which are

1. In an apparatus of the character described, the combination of a driving shaft, a motor, belt pulleys connected with said shaft and motor, a belt passing over said pulleys, an arm, a roller carried by said arm normally bearing in intimate contact against said belt, and a centrifugal governor carried by said shaft for automatically moving said arm and roller upon the speed of said shaft exceeding a predetermined number of revolutions per minute.
2. In an apparatus of the character described, the combination of a driving shaft, a motor, belt pulleys connected with said shaft and motor, a belt passing over said pulleys, an arm, a roller carried by said arm normally bearing in intimate contact against said belt, and a governor mounted upon said shaft, a collar connected with said governor, said collar being adapted to bear against

said arm whereby to move said roller to a point at which the same will bear lightly 45 against said belt.

3. In an apparatus of the character described, the combination of a driving shaft, a motor, belt pulleys connected with said shaft and motor, a belt passing over said pulleys, an arm, a roller carried by said arm normally bearing in intimate contact against said belt, a governor mounted upon said shaft, a collar connected with said governor, and slidably carried upon said shaft, said collar being adapted to bear against said arm whereby to move said roller to a point at which the same will bear lightly against said belt.

4. In an apparatus of the character described, the combination of a driving shaft, a motor, belt pulleys connected with said shaft and motor, a belt passing over said pulleys, an arm, a roller carried by said arm normally bearing in intimate contact against said belt, a governor mounted upon said shaft, and a conical collar adapted to bear against said arm whereby to move said roller to a point at which the same will bear lightly 60 against said belt.

5. In an apparatus of the character described, the combination of a driving shaft, a motor, belt pulleys connected with said shaft and motor, a belt passing over said pulleys, an arm, a roller carried by said arm normally bearing in intimate contact against said belt, a governor mounted upon said shaft, a collar bearing against a groove formed in said arm for moving said arm and roller to a point at which the latter 70 will bear lightly against said belt.

Signed at New York, in the county of New York and State of New York, this 26th day of October A. D. 1922.

HENRY LUBÉ.
